UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

FLUID-PRESSURE MOTOR.

Application filed July 11, 1921. Serial No. 483,778.

My invention relates to fluid pressure motors.

It has for its object to provide an improved fluid pressure motor. A further object of my invention is to provide an improved fluid pressure motor which is adapted to be constructed in relatively large sizes and at the same time prevent undesirable vibration. A still further object of my invention is to provide an improved fluid pressure motor preferably of the percussive type in which vibration resulting from checking the momentum of the piston upon the return stroke may be reduced to a minimum. A still further object of my invention is to provide an improved fluid pressure motor of the valveless percussive type in which improved cushioning means for the return stroke will be provided.

In the accompanying drawings I have shown, for purposes of illustration, three forms which my invention may assume in practice.

In these drawings,—

Fig. 1 is a diagrammatic view of one form of my improved construction, showing the piston about to begin its forward stroke, the view being taken substantially on the broken section line 1—1 of Fig. 6.

Fig. 2 is a similar view of the same form showing the parts with the piston at the opposite end of its stroke.

Fig. 3 is a diagrammatic view of another form of my improved construction, the piston being shown in the position corresponding to Fig. 1.

Fig. 4 is a similar view of this second form, showing the piston at approximately the opposite end of its stroke.

Fig. 5 is a diagrammatic view of a third form which my invention may assume in practice.

Fig. 6 is a transverse section on the line 6—6 of Fig. 1.

In the embodiment of my improved motor shown in Figures 1, 2, and 6, the motor comprises a cylinder 1 in which there reciprocates a piston generally indicated by 2 and having a striking bar 3 cooperating in a well known manner with a drill steel not shown. The piston 2 consists of two heads 4 and 5 connected by a reduced portion 7 about which there is formed an annular groove 6. The piston is bored out internally to form a supplemental cylinder 10 co-

axial with the piston and with this cylinder a projection or piston 11 attached to the rear head of the cylinder cooperates in a manner hereinafter described.

Fluid is distributed to the opposite ends 60 of the cylinder 1 and controlled in a manner similar to a well known commercial type of motor. Live fluid is supplied through a fluid pressure supply passage 12 which communicates at its forward end by means of 65 a passage 13 of reduced area with a storage chamber 14, and the fluid pressure supply passage 12 and storage chamber 14 are respectively provided with ports 15 and 16 longitudinally separated from each other by 70 a slight distance and opening into the bore of the cylinder near the center thereof. The supply of fluid to the opposite ends of the cylinder is controlled by the heads 4 and 5 and groove 6 of the piston, the groove 6 being 75 adapted to alternately connect one or both of the ports 15 and 16 with the opposite ends of the cylinder in a manner hereinafter described. The cylinder is likewise provided with suitable distribution passages 80 17 and 18 leading from points adjacent the middle of the cylinder to the opposite ends thereof, the passage 17 being provided with two supply ports 19 and 20, of which 19 constitutes a starting port, and at its opposite end communicating by means of a port 21 with the cylinder near its forward end. The passage 18 is provided with a supply port 22 and with a distribution port 23, the latter being located in the extreme rear end of 90 the cylinder. Suitable exhaust ports 8 and 9 are also provided and so disposed as to be uncovered by the opposite ends of the piston at appropriate times.

Cooperating with the cylinder 10 formed in the piston and with the projection 11 secured to the rear head of cylinder 1 is a supply passage 25 which extends centrally through the projection 11 and opens into the cylinder 10, this passage at its other end being connected by means of a pair of ports 26 and 27 with the bore of the cylinder, the passage 26 being located in relatively the same cylinder belt as the port 22 and the passage 27 being located somewhat further forward in the cylinder. It will be understood that the parts 10, 11, and ports 25, 26, and 27 and their spacial arrangement, both per se and in combination with the remainder of the construction, form a 105 110 115

part of my improvement in the above mentioned well known commercial type of motor.

The operation of my improved motor is as follows: Starting with the parts in the position shown in Fig. 1, fluid pressure is being transmitted from the passage 12 by way of port 15 to the cylinder bore where it is directed by the groove 6 formed in the piston to the port 22 and thence by way of passage 18 and port 23 to the rear end of the cylinder where it acts on the annulus of the piston 2 surrounding the projection 11. Fluid pressure is simultaneously admitted by way of port 26 to passage 25, which conducts fluid into the cylinder chamber 10 in the piston 2, where it acts upon the forward end of this cylinder and supplements in effect the pressure acting on the rear end of the piston. Under the combined action of the motive fluid in the rear end of the cylinder 1 and the cylinder 10, the piston moves forward and at, or about mid-stroke, communication is closed between the port 15 and the port 22, after which further action of the pressure in the rear end of the cylinder 1 is expansive only. Substantially simultaneously with cut off in the rear end of the cylinder, fluid pressure is admitted from both fluid pressure supply passage 12 and from storage chamber 14, the latter of which was previously for a short time in communication with port 22, to port 19 and thence by way of passage 17 and port 21 to the front end of the cylinder. At about the moment when port 15 is closed, port 20 is opened and live fluid flows by way of port 16 out of storage chamber 14, supplemented in part by the stored pressure therein, and passes to the front end of the cylinder where it accumulates for the purpose of making a return stroke, and where it acts, when sufficient pressure has been built up, to partially cushion the extreme end of the forward stroke, the latter effect, however, being only negligible during drilling operation of the motor, but becoming effective when the motor is being run idly and is not acting on a drill; at which time the stroke is, of course, considerably longer as it is checked only by the cushion. Just before the end of said stroke, the communication of port 27 with the fluid pressure supply is closed by its being overrun by the rear head of the piston. It will accordingly be noted that live fluid has acted for a considerably longer time, perhaps 40% of the stroke, on the portion of the piston exposed to pressure in cylinder 10, whereby the power of the stroke is increased and an earlier, but light, cushioning effect on the rear stroke will be accomplished. Upon the return stroke, it will be noted that the port 27 will be opened very much earlier than is the port 22 and accordingly, as just stated, a much earlier partial

cushioning effect will be obtained, and even before the opening of the port 27 a cushioning effect to a lesser degree will be obtained due to the fact that the fluid pressure in cylinder 10 was only partially expanded and will accordingly resist movement of the piston to some extent before live pressure is again admitted, this resistance progressively increasing due to the compression of the pressure in the cylinder 10 until the moment when a pressure equal to that of live fluid will have again been reached. Throughout the remainder of the return stroke, live pressure will continue to act in the cylinder 10 to cushion and more nearly equalize the velocity of movement of the return pass of the piston. As a result of this construction, it will be found that greater forward speed will offset slightly reduced return speed and the vibration of the motor due to the sudden stopping of the motion of a relatively heavy piston moving at a relatively high velocity will be largely done away with. The location of the port 22, as a result of this construction, may be changed, of course, somewhat from its position in the commercial construction heretofore mentioned, this port being moved somewhat further to the rear end of the cylinder and accordingly the main cushioning action of the piston need not commence at quite so early a time in the stroke.

The modification shown in Figures 3 and 4 is very closely related in both function and structure to that shown in Figures 1 and 2, the chief difference being that I have provided an exhaust port for the purpose of permitting the escape of the fluid which has been acting in the cylinder 10 therefrom at approximately the forward limit of the piston stroke, the purpose of this exhaust being to permit the starting of the piston on its return travel with no pressure acting to resist its motion. In this construction the passage 25' is made larger than was the passage 25 for a considerable portion of its length and communicates with the cylinder bore 1 at three longitudinally separated points instead of at two. The ports 26' and 27' are located at substantially the same positions as were the ports 26 and 27, but an additional passage 28 is provided which is so located as to be uncovered by the rear end of the piston head 4 at or preferably just after the moment when the exhaust port for the rear end of the cylinder is uncovered. At this time the ports 26' and 27' are both closed and accordingly there is no loss of live fluid by direct passage from the inlet to the exhaust, but such fluid as is stored in the cylinder 10 and in the various passages is free to pass out through the exhaust port. The passages 26' and 27' and the forward portion of the passage 25' which is formed in the cylinder wall is of less diameter than is

the remainder of the passage, this being for the purposes of controlling the fluid pressure supply by the port areas of the connections 26' and 27' while providing ample area 5 for the exhaust port.

The operation of this form of my invention is, in the general details of fluid distribution to the opposite ends of the cylinder 1, the same as in the first form, but the cylinder 10 is exhausted at the forward end of 10 the piston stroke and accordingly the initial motion of the piston on its return stroke is not cushioned and so a slightly quicker start can be obtained.

15 In Figure 5 I have shown a still further form of my invention and one which is simpler than either of those previously described. In this case the passage 27 is entirely omitted and no exhaust port is provided for the cylinder 10, the port 26" being closed substantially at the same time as the port 22. The operation in this case is that the fluid entrapped in the chamber 10 at the moment of closure of port 26" acts 20 expansively therein during the remainder of the stroke and thereafter is recompressed up to initial pressure until the time when the port 26" is reopened. In this case I rely upon the recompression of the expanded 25 fluid to provide the equalization by the slight initial retardation of the piston, this construction, however, differing from the previously described construction of Figures 3 and 4 in that, instead of exhausting and re- 30 supplying the fluid, I obtain the same low pressure effect in the beginning of the stroke by a considerable degree of expansion in the entrapped fluid and thereafter recompress 35 the same instead of readmitting a supply of 40 fluid.

In all the forms of my invention herein shown for purposes of illustration, the common feature is the provision of means acting to accelerate the velocity during the forward 45 stroke and to slightly advance the beginning of cushioning on the return stroke whereby the piston does not acquire so extreme a velocity toward the middle of its return stroke and accordingly such a great reaction upon 50 the stopping of the piston at the end of the stroke is not required. Accordingly, the same effect can be obtained in the matter of power and speed of operation by setting back 55 the admission port for the rear end of the cylinder a slight distance toward the rear end of the cylinder and a relatively vibrationless motor may be obtained.

While I have in this application specifically described three forms which my invention may assume in practice, it will be understood that these forms of the same are shown for purposes of illustration and that the invention may be modified and embodied 60 in other forms without departing from its spirit or the scope of the appended claims. 65

What I claim as new and desire to secure by Letters Patent is:

1. In a fluid pressure drilling motor, the combination with, a cylinder, a piston therein, and means for distributing fluid under pressure alternately to the opposite ends thereof and for exhausting used fluid, of fluid cushioning means controlled by said piston for subjecting a portion thereof to fluid pressure resisting the rearward movement thereof, before the moment when the first mentioned fluid distributing means for the rear end of said cylinder is operative. 70

2. In a fluid pressure drilling motor, the combination with a cylinder, a piston therein, and means for distributing fluid under pressure alternately to the opposite ends thereof and for exhausting used fluid, of fluid cushioning means cooperating with said piston for subjecting a portion thereof 80 intermittently to fluid pressure for resisting rearward movement of said piston, before the moment when the first mentioned fluid distributing means for the rear end of said cylinder is operative. 85

3. In a fluid pressure drilling motor, the combination, with a cylinder, a piston reciprocable therein, and piston controlled means for distributing fluid pressure alternately to the front and rear ends of the cylinder and for the exhaust of used fluid therefrom, of fluid cushioning means for subjecting a portion of said piston to fluid pressure for substantially the entire rearward stroke of said piston to oppose rearward movement thereof, said piston controlled means being operable independently of said latter means. 90

4. In a fluid pressure drilling motor, the combination with a cylinder, a piston reciprocable therein, and piston controlled means for distributing fluid pressure alternately to the front and rear ends of the cylinder and for the exhaust of used fluid therefrom, of fluid cushioning means for subjecting a portion of said piston to fluid pressure for substantially the entire rearward stroke of said piston to oppose rearward movement thereof, said means being operative to provide a pressure less than the inlet pressure to resist return motion of said piston at the beginning of the rearward pass of said piston. 100

5. In a fluid pressure drilling motor, the combination with a cylinder, a piston therein, means for distributing fluid under pressure to the opposite ends thereof for a portion of the strokes in each direction, and means for exhausting used fluid, of fluid cushioning means comprising a projection fixed to one of said first mentioned elements and a cylinder formed in the other together with means for supplying fluid pressure thereto, said projection and cylinder always having a substantially non-leak fit, to control the velocity of the piston during the return stroke of the piston. 110

6. In a fluid pressure drilling motor, a cylinder, a piston therein, means for distributing fluid under pressure to the opposite ends thereof for a portion of the strokes in each direction, means for exhausting used fluid, and means comprising a projection fixed to said cylinder and a cylinder formed in said piston together with means for supplying fluid pressure thereto, to control the velocity of the piston during the return stroke of the piston, fluid flow to said opposite ends being effected independently of said latter fluid flow.

7. In a fluid pressure drilling motor, a cylinder, a piston therein, means for distributing fluid under pressure alternately to the opposite ends thereof and exhausting used fluid therefrom, said distributing means being operative to supply fluid to each end of said cylinder prior to the completion of the stroke toward that end, and means comprising a cylinder formed in one of said first mentioned elements and a projection secured to the other thereof, together with means for periodically admitting fluid to said latter cylinder prior to the admission of fluid to the end of said first mentioned cylinder adjacent which said second mentioned cylinder and projection are arranged, whereby to regulate the velocity of the stroke toward that end of the cylinder.

8. In a fluid pressure drilling motor, a cylinder, a piston reciprocable therein, means for distributing fluid under pressure to the opposite ends thereof and exhausting used fluid therefrom, and means controlled by the piston to admit intermittently fluid pressure to a portion of the piston during its rearward movement.

40 9. In a fluid pressure drilling motor, a cylinder, a piston reciprocable therein, fluid supply means, piston controlled means for distributing fluid pressure alternately to and from the rear ends of the cylinder and for the exhaust of used fluid therefrom, and means for subjecting a portion of said piston to fluid pressure for only substantially the entire rearward stroke of said piston to oppose rearward movement thereof.

50 10. In a fluid pressure drilling motor, a cylinder, a piston reciprocable therein, means for distributing fluid under pressure to the opposite ends thereof and exhausting used fluid therefrom, and means controlled by the piston to admit fluid within said piston during only a portion of the cycle of movement of said piston to resist rearward movement and to assist forward movement of said piston.

60 11. In a fluid pressure drilling motor, a cylinder, a piston reciprocable therein, fluid pressure distributing means to supply pressure alternately to the opposite ends of the cylinder and to exhaust used fluid therefrom, and means arranged concentrically

within the piston and separate from the fluid distributing means to control the velocity of said piston by exerting a varying force on said piston.

12. In a fluid pressure drilling motor, a cylinder, a piston reciprocable therein, means for distributing fluid under pressure alternately to the opposite ends thereof and exhausting used fluid therefrom, said distributing means being operative to supply fluid to each end of said cylinder prior to the completion of the stroke toward that end, and means comprising a cylinder having a bore of uniform dimensions formed in one of said first mentioned elements and a piston constituting member secured to the other thereof and having a continuous running fit in said bore, a ported passage leading thereto and means controlled by said motor piston to close said port at a predetermined point in the travel of the piston.

13. In a fluid pressure drilling motor, a cylinder, a piston reciprocable therein, an inlet port, means for distributing fluid under pressure to the opposite ends of the cylinder and exhausting fluid therefrom, and means for intermittently subjecting a portion of the piston to fluid pressure resisting the rearward movement thereof before the instant when the first mentioned fluid distributing means for the rear end of said cylinder is operative.

14. In a fluid pressure drilling motor, a cylinder, a piston reciprocable therein, fluid pressure means for cushioning the rearward stroke of said piston, and means for supplying actuating fluid to opposite ends of said piston operable independently of fluid flow to said other means.

15. In a fluid pressure drilling motor, a plurality of relatively small and large piston and cylinder elements, one of which is disposed at the rear of the other, means for supplying fluid to opposite ends of the larger cylinder, and means for supplying live pressure fluid intermittently to said smaller cylinder.

16. In a fluid pressure drilling motor, a plurality of relatively small and large piston and cylinder elements, one of which is disposed at the rear end of the other, means for supplying fluid to opposite ends of the larger cylinder, and means for supplying intermittently fluid under pressure above atmosphere to said smaller cylinder upon the rearward stroke of said piston.

17. In a fluid pressure drilling motor, a plurality of sets of piston and cylinder elements, means whereby fluid may be supplied to act on one of said pistons to effect fluid cushioning of said other piston, and means for exhausting said cushioning fluid.

18. In a fluid pressure drilling motor, the combination with a cylinder and a piston reciprocable therein having a cylindrical bore,

of fluid cushioning means for said piston comprising a piston extending within said bore, and means for supplying fluid to said bore and exhausting it therefrom.

5 19. In a fluid pressure drilling motor, a cylinder, a piston reciprocable therein having a cylindrical bore, a piston extending within said bore, and means for supplying fluid to said bore and exhausting it therefrom, said means including a common passage.

10 20. In a fluid pressure drilling motor, a cylinder, a piston reciprocable therein having a cylindrical bore, a piston extending within said bore, and means for supplying fluid to said bore and exhausting it therefrom, said means including a common passage and branch passages.

21. In a fluid pressure drilling motor, a cylinder, a piston reciprocable therein having a cylindrical bore, a piston extending within said bore, and means for supplying fluid to said bore and exhausting it therefrom, said means including a common passage and branch passages adapted respectively to conduct live fluid and exhaust fluid. 20

22. In a fluid pressure drilling motor, a cylinder, a piston reciprocable therein having a cylindrical bore, a piston extending within said bore, and means for supplying fluid to said bore and exhausting it therefrom, said means including a common passage controlled by said reciprocable piston. 25

In testimony whereof I affix my signature.

ELMER G. GARTIN.
